WILLIAM HORACE SODEAU, OF NEWCASTLE-UPON-TYNE, ENGLAND,
ASSIGNOR TO SIR W. G. ARMSTRONG, WHITWORTH AND COMPANY,
LIMITED, OF NEWCASTLE-UPON-TYNE, ENGLAND.

MEANS FOR INCREASING THE WORK OBTAINABLE FROM A CHARGE OF COMPRESSED AIR.

No. 827,891.

Specification of Letters Patent.

Patented Aug. 7, 1906.

Application filed May 9, 1905. Serial No. 259,580.

To all whom it may concern:

Be it known that I, WILLIAM HORACE SODEAU, engineering chemist, a subject of the King of Great Britain, residing at Elswick Works, Newcastle-upon-Tyne, England, have invented certain new and useful Improvements in or Relating to Means for Increasing the Work Obtainable from a Charge of Compressed Air, more particularly applicable to the propulsion of torpedoes and the like, of which the following is a specification.

This invention relates to improvements in the apparatus described in the specifications Nos. 693,871 and 693,872, dated the 25th of February, 1902. According to these specifications the amount of work obtainable from a charge of compressed air stored in a reservoir—as, for example, in the reservoir of a Whitehead torpedo—is increased by burning inside the reservoir alcohol, petroleum, or other suitable combustible liquid, so that the temperature of the air is raised and the volume which it will occupy at a given pressure consequently increased.

The invention could of course be applied to a reservoir containing instead of air any other gas or gases capable of supporting combustion.

With a single fuel-reservoir arranged as described in the above-mentioned specifications the rate at which the combustible liquid is fed into the air-reservoir, owing to the expansion of the air contained in the upper part of the fuel-reservoir, increases very greatly as the pressure decreases, assuming the pressure to fall at a constant rate. The rate of feed is, in fact, approximately proportional to the square of the reciprocal of the pressure in the air-reservoir. Consequently dangerously high temperatures are apt to be produced in the later stages if the air-space in the fuel-reservoir is large enough to cause the delivery of combustible liquid to take place at a rate sufficiently great to produce a rapid rise of temperature during the early stages of the discharge of the air from the reservoir. Conversely, there will at first be a relatively slow rise of temperature if the air-space is proportioned to produce a reasonable temperature toward the termination of the discharge.

According to this invention the progressive feeding of the combustible liquid into

the air-reservoir is dependent upon the fall of pressure in the latter. For this purpose I employ two or more fuel-reservoirs in which there are different relationships between the air-space and combustible liquid. The sum of the air-spaces in all the fuel-reservoirs is such that the expansion of the air confined in these air-spaces feeds the combustible liquid at the desired rate during the earlier stages of the discharge from the air-reservoir—that is to say, the combustible liquid is fed into the air-reservoir at such a rate that its combustion causes the temperature of the issuing air to rise as rapidly as is desirable having regard to the safety of the engine, &c. The ratio of combustible liquid to air-space in the various fuel-reservoirs is so proportioned that the combustible liquid in the one in which the ratio is smallest will have been entirely expelled before the rate of feed has become excessive. This emptying of one of the fuel-reservoirs causes a sudden reduction of the rate of feed, and so prevents the production of an injuriously high temperature. As the discharge from the air-reservoir continues there will again be an increase in the rate of feed from the remaining fuel reservoir or reservoirs, which is prevented from becoming excessive by the successive emptying of the various fuel-reservoirs (if more than two are employed) in the inverse order of their ratio of fuel-space to air-space.

The drawing is a part longitudinal section of a torpedo constructed according to this invention.

a b are two fuel-reservoirs having different ratios of air-space to fuel-space which I employ for the purpose of obtaining a suitable gradation of the fuel-supply.

c is the compressed-air reservoir, communicating with reservoirs *a* and *b* by the pipe *d*. *e* is a valve on this pipe. The initial rate of flow of fuel through the pipe *d* is due to the expansion of the air in both *a* and *b*; but at a desired stage the reservoir *a*, which has a relatively large air-space, will have become empty. The fuel-supply is then obtained only from *b*, so that the rate of feed is then much less than if the whole of the air originally contained in the fuel-reservoirs was still driving out combustible liquid by its expansion. Conversely, the initial rate of feed

is much greater than if the air-space in *a* had not been acting during the early stages.

f is a spraying-nozzle at the end of the pipe *d*, or the dish-like furnace described in the said former specifications may be employed.

g is the primer or cartridge for igniting the spray.

a' b' are the pipes for charging the fuel-reservoirs *a* and *b*. As shown, these pipes dip 10 different distances into the fuel-reservoirs *a* and *b*, so that the amount of fuel which can be charged into the respective reservoirs is also different.

h is the pipe, leading the compressed air 15 from the reservoir *c* to the engine.

The fuel-reservoirs may be placed inside instead of outside the reservoir *c*; but this is not usually convenient.

When a spraying-nozzle is employed, its 20 throttling action tends to check the increase in the rate at which the fuel is fed in the later stages.

I have shown the source of fuel as consisting of two reservoirs, though this number is 25 not essential. The fuel in the reservoirs at first stands at different levels, and all of it is under fluid-pressure. Before complete delivery of the fuel to the air-reservoir a part of the pressure on the fuel is automatically released, as when the first reservoir in the series 30 containing least fuel is emptied, and thus the normal increase of the rate of delivery of the fuel due to the fall of pressure in the air-reservoir is automatically checked during the 35 delivery of the fuel.

What I claim is—

1. The combination with apparatus for heating a body of compressed air of the type in which liquid fuel is fed into the compressed

40 air by the expansion of a second body of compressed air, of means for allowing part of the second body of compressed air to escape before the whole of the fuel has been delivered.

2. The combination of a reservoir for compressed air, a source of fuel under pressure connected therewith, means for igniting and burning the fuel in the air-reservoir, and means for releasing a portion of the pressure on the fuel before complete delivery thereof 50 whereby a suitable gradation of the supply of fuel is effected.

3. The combination of a reservoir for compressed air, a source of fuel under pressure connected therewith, means for igniting and burning the fuel in the air-reservoir and means 55 for automatically releasing a portion of the pressure on the fuel before complete delivery thereof, the arrangement being such that the normal increase of the rate of delivery of the fuel due to the fall of pressure in the air-reservoir is automatically checked during the delivery of the fuel.

4. The combination of a reservoir for compressed air, a source of fuel under fluid-pressure connected therewith, and means for auto-

matically withdrawing a portion of the pressure fluid from the fuel before complete delivery of the fuel to the air-reservoir.

5. The combination of a reservoir for compressed air, a plurality of closed fuel-reservoirs 70 communicating with it by a common passage and containing respectively bodies of fuel under pressure at different levels whereby the fuel-reservoirs are successively emptied and means for igniting and burning 75 the fuel in the air-reservoir.

6. The combination of a reservoir for compressed air, a plurality of reservoirs respectively containing different quantities of fuel under pressure, connections between said 80 fuel-reservoirs and the reservoir for compressed air, and means for igniting and burning the fuel in the air-reservoir.

7. The combination of a reservoir for compressed air, a plurality of reservoirs 85 respectively containing different quantities of fuel under pressure, and a pipe connected to the fuel-reservoirs and having one end in the air-reservoir.

8. The combination of a reservoir for compressed air, a plurality of reservoirs 90 respectively containing different quantities of fuel under pressure, a pipe connected to the fuel-reservoirs and having one end in the air-reservoir, and a spraying-nozzle on this end of 95 the pipe.

9. The combination of a reservoir for compressed air, a plurality of reservoirs respectively containing different quantities of fuel under pressure, a pipe connected to the fuel-reservoirs and having one end in the air-reservoir, a spraying-nozzle on this end of the pipe, and a valve between this end and the fuel-reservoirs.

10. The combination of a reservoir for compressed air, a plurality of reservoirs 105 respectively containing different quantities of fuel under pressure, a pipe connected to the fuel-reservoirs and having one end in the air-reservoir, and a valve between this end and the 110 fuel-reservoirs.

11. The combination of a reservoir for compressed air, a plurality of reservoirs for fuel under pressure communicating with it, fuel-charging pipes dipping into the fuel-reservoirs, the ratio of the volume of the reservoirs above the bottom of the charging-pipe 115 to the volume below it being different in the different reservoirs, and means for igniting and burning the fuel in the air-reservoir. 120

12. The combination of a reservoir for compressed air, a plurality of reservoirs for fuel under pressure, fuel-charging pipes dipping into the fuel-reservoirs, the ratio of the volume of the reservoir above the bottom of the 125 charging-pipe to the volume below it being different in different reservoirs, and a pipe connected to the fuel-reservoirs and having one end in the air-reservoir.

13. The combination of a reservoir for com-

pressed air, a plurality of reservoirs for fuel under pressure, fuel-charging pipes dipping into the fuel-reservoirs, the ratio of the volume of the reservoir above the bottom of the charging-pipe to the volume below it being different in the different reservoirs, a pipe connected to the fuel-reservoirs, and having one end in the air-reservoir, and a spraying-nozzle on this end of the pipe.

14. The combination of a reservoir for compressed air, a plurality of reservoirs for fuel under pressure, fuel-charging pipes dipping into the fuel-reservoirs, the ratio of the volume of the reservoir above the bottom of the charging-pipe to the volume below it being different in the different reservoirs, a pipe connected to the fuel-reservoirs and having

one end in the air-reservoir, a spraying-nozzle on this end of the pipe, and a valve between this end and the fuel-reservoirs.

15. The combination of a reservoir for compressed air, a plurality of reservoirs for fuel under pressure, fuel-charging pipes dipping into the fuel-reservoirs, the ratio of the volume of the reservoir above the bottom of the charging-pipe to the volume below it being different in the different reservoirs, a pipe connected to the fuel-reservoirs and having one end in the air-reservoir, and a valve between this end and the fuel-reservoirs.
